UNITED STATES PATENT OFFICE.

JOHN A. PROCTOR, OF REVERE, MASSACHUSETTS, ASSIGNEE TO WIRELESS SPECIALTY APPARATUS COMPANY, OF BOSTON, MASSACHUSETTS, A CORPORATION OF NEW YORK.

RADIO RECEIVING APPARATUS.

1,211,963.

Specification of Letters Patent. Patented Jan. 9, 1917.

Application filed June 28, 1914. Serial No. 847,827.

To all whom it may concern:

Be it known that I, JOHN A. PROCTOR, a citizen of the United States of America, and a resident of Revere, Massachusetts, have invented certain new and useful Improvements in Radio Receiving Apparatus, the principles of which are set forth in the following specification and accompanying drawing, which disclose the form of the invention which I now consider to be the best of the various forms in which the principles of the invention may be embodied.

This invention relates to improvements in radio receiving apparatus, the object being such an apparatus which shall be adapted to be operated by oscillations produced by continuous or undamped electric waves, without the employment of any form of make-and-break device which devices are disadvantageous because they cause a non-sinusoidal current in the telephones with resulting inefficient response.

The invention consists of the apparatus and arrangements shown in the drawings, which are diagrammatic and in which continuously-variable condensers are shown in Figures 1 and 2 in different relations.

In both figures, A is the antenna, G the ground connection, P and S the primary and secondary of the coupling transformer, D the detector and T the telephones; also the arrow heads on connections indicate adjustability. In Fig. 2 the telephones T are shunted by a fixed condenser C, but in Fig. 1 detector D is shunted around the telephones T. In Fig. 1, a condenser K, adjustable at the will of the operator, is connected to the secondary S, but in Fig. 2 this condenser is made continually variable. In accordance with this invention, the variation of the oscillations of the current delivered to the detector is made smooth, and preferably sinusoidal, between zero and maximum, by means of a continuously variable condenser. For example, as in Fig. 1, condenser C' is introduced between detector D and secondary circuit S, K, its movable element being mounted as a spindle B' which may be rotated (as by a motor) at a rate of from 200 to 500 times a second, to vary the capacity

smoothly from zero to maximum, and produce a corresponding note in the telephones T.

In Fig. 2, the manually adjustable condenser K of Fig. 1, an element of the secondary circuit with secondary winding S, is replaced by condenser K' which may be constructed and operated precisely like condenser C' of Fig. 1, just above described. But the electrical operation of this arrangement is to vary smoothly the tune of the secondary circuit, whereby the energy of the received continuous oscillations is caused to produce a corresponding note in the telephones T.

Bearing in mind the fact that the variation required for the oscillations of the current delivered to the detector, are of the order of several hundreds of periods per second, (in order to correspond to the mechanical period of the telephone), the advantage will be appreciated of employing for this purpose a device which can be constructed to have a very light and well-balanced rotating part, such as the continuously variable condenser employed in this invention. This method of varying the oscillations is, for that reason, far superior to any method involving a rotating coil of wire, for while such a device may be rotated sufficiently rapidly to merely operate, yet it is impracticable if not impossible, to rotate it fast enough to produce the desired high note in the telephone.

I claim:

In a receiver of continuous oscillations, the combination with an antenna, of a detector and a telephone receiver, all co-operatively arranged, and a variable condenser connected to vary the oscillations passing to the detector, said condenser being constructed to be continuously rotated at a high speed to produce oscillation-variations of a frequency corresponding to the operating period of the telephone receiver.

JOHN A. PROCTOR.
